UNITED STATES PATENT OFFICE.

CHARLES H. BUNTING, OF PITTSBURG, PENNSYLVANIA, ASSIGNOR TO WEBER-ERICKSON-BUNTING COMPANY, OF PITTSBURG, PENNSYLVANIA, A CORPORATION OF PENNSYLVANIA.

DESIGN FOR A WATCH-FOB.

No. 39,461.

Specification for Design.

Patented Aug. 25, 1908.

Application filed June 6, 1908. Serial No. 437,205. Term of patent 3½ years.

To all whom it may concern:

Be it known that I, CHARLES H. BUNTING, a citizen of the United States, residing at Pittsburg, in the county of Allegheny, State of Pennsylvania, have invented a new, original, and ornamental Design for a Watch-Fob, of which the following is a specification, reference being had to the accompanying drawing, forming part thereof.

The figure is a plan view of a watch fob showing my new design.

What I claim is:

The ornamental design for a watch fob as shown.

CHARLES H. BUNTING.
